SAFETY DEVICE FOR CONTAINER MOVING MACHINERY

Stanley R. Rosendale, Mount Healthy, Ohio, assignor to The Karl Kiefer Machine Company, Cincinnati, Ohio, a corporation of Ohio

Application September 16, 1936, Serial No. 101,111

8 Claims. (Cl. 192—150)

I shall describe my invention in connection with means for moving bottles, which may in turn be thought of as part of a bottle filling machine, it being understood that these are exemplary only 5 of fields of utility for my invention. My invention will be equally applicable, as will be appreciated by one skilled in the art, to the handling and movement of all sorts of containers and to 10 articles which could be crushed, marred and broken by failure of mechanical means properly to function.

I shall describe my invention also in connection with star wheel means for moving bottles in a circular path or for changing the direction 15 of movement thereof. The star wheel in combination with guide means is well known; and it has also been understood in the art that there was a necessity for some sort of safety means operative to stop the star wheel if the bottles fail 20 properly to feed into the star wheel spaces, so as to avoid jamming and breaking of the bottles. The suggestion of the prior art comprised hinging a section of the guide and connecting the hinged section with a clutch located at a convenient 25 point in the power transmission chain of the mechanism. This is operative to the end of stopping the mechanism upon actual displacement of the bottles.

It will be clear, however, that it involves certain 30 operating disadvantages. When, for different sized bottles or containers it becomes necessary to change the star wheel and guide, a new connection between the hinged section of the guide and the clutch must be made. This is a 35 matter of rather delicate adjustment, and the time consumed seriously cuts down the operating capacity of the machine. Also the safety mechanism operates only if a jam occurs at the hinged section of the guide.

It is an object of my invention to provide a 40 safety means not subject to these disadvantages. It is an object of my invention to provide a structure in which changing the star wheel and guide requires no change in or readjustment of the safety mechanism.

It is an object of my invention to provide a 45 safety means which is sensitive to and operative upon the occurrence of any undue pressure against or resistance to the motion of the star 50 wheel or its equivalent.

It is an object of my invention to provide a 55 safety device which will stop the mechanism if a jam occurs anywhere around the circumference of the star wheel.

These and other objects of my invention which

will be set forth hereinafter or will be apparent to one skilled in the art upon reading these specifications, I accomplish by that certain construction and arrangement of parts of which I shall now describe the aforesaid exemplary embodiment. Reference is made to the accompanying drawing in which:

Fig. 1 is a top plan view of a means for moving bottles including a star wheel, guide and conveyor.

Fig. 2 is a sectional view of the mechanism taken along the lines 2—2 of Fig. 1.

Fig. 3 is an elevational view of the mechanism of Fig. 2 (with the conveyor in section), the view being taken along the lines 3—3 of Fig. 2; and

Fig. 4 is a sectional view of the clutch mechanism taken along the lines 4—4 of Fig. 5.

In Fig. 1 I have shown a simple means for changing the direction of motion of bottles 5 moving along a conveyor 6. A guide means 7 20 aligns the bottles so that they may be positioned in the interspaces of the star wheel, and also serves to keep the bottles in these interspaces during rotation of the star wheel. The simple mechanism shown will serve to illustrate the 25 principles of my invention it being understood, of course, that my invention is applicable to other mechanism, and in particular that instead of the small star wheel shown a much larger mechanism may be employed in connection with which the 30 bottles, as they move about the periphery of the wheel, may be subjected to various treatments, such, for example as cleaning or filling.

Referring to Fig. 2, the star wheel 8 is keyed or otherwise non-rotatably fastened to a shaft 9 35 which is suitably journaled in the frame 10 of the machine. A gear 11 is rotatably mounted on the shaft 9 and may be held in position by a collar 12. The gear 11 meshes with a driving gear 13, which through certain transmission means 40 (not shown) and through a clutch which will hereinafter be described is connected to a source of power for the machine.

A plate 14 is bolted as at 15 to the gear 11 so as to rotate therewith; and it bears one or more 45 projecting pins 16. These pins engage detent means 17 on a collar 18 slidably splined to the shaft 9. The engagement of the pins with the detent means is the means for transmitting motion from the gear 11 to the star wheel shaft 9; 50 and the detent means are tapered in form so that if there is resistance to the movement of the shaft 9 the pins 16 can depress the collar 18 permitting the shaft to remain stationary in spite of rotation of the gear 11.

The collar is held upwardly by a lever 20, pivoted as at 21 to a bracket 22 on the bed of the machine. An end of this lever bears against a thrust bearing 23 on the collar 18. The other 5 end of the lever is urged downwardly by a compression spring 24 which may be adjusted by means of a set screw 25, threaded in the bracket 22, or by equivalent adjusting means. By such means the degree of pressure exerted by the lever 10 20 can be adjusted so that the sensitivity of the safety mechanism can be made anything desired.

It is desirable to stop the mechanism upon actuation of the safety means, and I shall now describe the provision made for this purpose. As 15 shown in Fig. 3, a transverse shaft 26 is suitably journaled in the bracket 22 and in another bracket 27. This shaft bears a pair of arms 28 for operating a clutch. This clutch is shown in section in Fig. 4. The main operating shaft of the 20 machine is shown at 29 and is indicated as bearing a pulley 30, to which power is transmitted for the machine by means of a belt 31 or otherwise as may be desired. The pulley is free to rotate on the shaft but is connected with a clutch part 25 indicated at 32. A corresponding clutch part 33 is splined on the shaft 29 so as to be slidable thereon. This clutch part is operated by the arms 28 as will be readily understood. The particular form of the clutch is not a limitation on 30 my invention, and may be any desired. I have shown a simple form of clutch, having teeth.

The shaft 26, near its other end (as shown most clearly in Fig. 2) bears another arm 34. This arm carries a detent 35 adapted to engage 35 a corresponding detent on the lever 20 as shown in Fig. 2. The arm 34, is, however, urged clockwise by suitable means, and to this end I have provided a rod 37 attached to the arm 34 and passing through the bracket 22. A compression 40 spring 38 engages the bracket abutment 39 on the rod 37. In the position of the elements shown in Fig. 2, the clutch is engaged but it is maintained in engagement only by the lever 20, which, as before explained, acts as a latch. 45 Should the left hand end of the lever 20 be raised (as would happen for example, if the collar 18 were forced downwardly by the pins 16) the clutch would be instantly disengaged as will be clear.

50 In order to provide for the reengagement of the clutch, an operating lever 40, is attached to the shaft 26 and is provided with a handle 41. Assuming that power is being supplied to the pulley 30, the handle 41 acts as a starting handle 55 for the machine. When it is thrown to the left in Fig. 2, the clutch is engaged and the arm 34 is latched by the lever 20.

Should one of the bottles 5 jam in the mechanism, the added resistance imposed on the star 60 wheel 8 will cause the pins 16 to force the collar 18 downwardly, thus releasing the shaft 9 on which the star wheel is mounted. At the same time, however, the collar depresses the right hand end of the lever 20 and raises the left hand end 65 of it, thereby releasing the arm 34. The action of the spring 38 is to rock the shaft 26, thereby throwing out the clutch.

In order to provide means for stopping the 70 mechanism, when desired, I pivot a lever 42 on ears 43 on the bracket 22. The lever is provided with an operating handle 44. At its pivoted end it bears a bell crank 45, which is connected by a suitable linkage with the lever 20, so that when the lever 42 is rocked clockwise in Fig. 3, it will 75 raise the latching end of the lever 20. It is well

to have a lost motion connection between the lever 20 and the end of the bell crank 45. To this end, I employ a rod 46, passing through the lever 20, and having an abutment 47 thereon. A compression spring 48 engages between the 5 lever 20 and another abutment 49 on the rod.

The operation of my mechanism will be clear from the foregoing; but it will be understood that modifications may be made in my invention without departing from the spirit thereof, and that 10 what I claim as new and desire to secure by Letters Patent, is:

1. In a safety device of the character described 15 a shaft to be driven, driving means rotatably mounted on said shaft, a collar slidably but non-rotatably mounted on said shaft and interengagement means on said driving means and on said collar, at least one of said interengagement means being beveled so that relative rotation of said driving means and said shaft causes displacement of said collar axially of said shaft, and means for urging said collar toward said driving means with a predetermined force, said means comprising a lever and adjustable spring 20 means bearing against said lever, a clutch, operating means for said clutch including an arm, said arm being located in a position of latching engagement with said lever when said clutch is in motion-transmitting engagement.

2. In a safety device of the character described 30 a shaft to be driven, driving means rotatably mounted on said shaft, a collar slidably but non-rotatably mounted on said shaft and interengagement means on said driving means and on said collar, at least one of said interengagement 35 means being beveled so that relative rotation of said driving means and said shaft causes displacement of said collar axially of said shaft, and means for urging said collar toward said driving means with a predetermined force, said means 40 comprising a lever and adjustable spring means bearing against said lever, a clutch, operating means for said clutch including an arm, said arm being located in a position of latching engagement with said lever when said clutch is in 45 motion-transmitting engagement, and manual means for bringing said arm and said lever into latching engagement.

3. In a safety device of the character described 50 a shaft to be driven, driving means rotatably mounted on said shaft, a collar slidably but non-rotatably mounted on said shaft and interengagement means on said driving means and on said collar, at least one of said interengagement 55 means being beveled so that relative rotation of said driving means and said shaft causes displacement of said collar axially of said shaft, and means for urging said collar toward said driving means with a predetermined force, said means comprising a lever and adjustable spring means 60 bearing against said lever, a clutch, operating means for said clutch including an arm, said arm being located in a position of latching engagement with said lever when said clutch is in motion-transmitting engagement, and manual means for bringing said arm and said lever into 65 latching engagement, and additional manual means for moving said lever to release said engagement.

4. In a machine of the class described a drive 70 shaft and a driven shaft, a clutch on said drive shaft, a connection between said drive shaft and said driven shaft, including a member rotatable on said driven shaft, a member splined on said 75

driven shaft and having means for engagement with said rotatable member, said engagement means being such as to produce axial displacement of said splined member if said driven shaft ceases to rotate with said rotatable member, and a connection between said splined member and said clutch, comprising a lever, operating means for said clutch comprising a shaft, a connection between said shaft and said clutch, and an arm on said shaft adapted to be latched by said lever.

5. In a machine of the class described a drive shaft and a driven shaft, a clutch on said drive shaft, a connection between said drive shaft and said driven shaft, including a member rotatable 15 on said driven shaft, a member splined on said driven shaft and having means for engagement with said rotatable member, said engagement means being such as to produce axial displacement of said splined member if said driven shaft ceases to rotate with said rotatable member, and a connection between said splined member and 20 said clutch, comprising a lever, operating means for said clutch comprising a shaft, a connection between said shaft and said clutch, an arm on said shaft adapted to be latched by said lever, and a starting operating handle affixed to said shaft.

6. In a machine of the class described a drive shaft and a driven shaft, a clutch on said drive shaft, a connection between said drive shaft and said driven shaft, including a member rotatable on said driven shaft, a member splined on said driven shaft and having means for engagement with said rotatable member, said engagement 35 means being such as to produce axial displacement of said splined member if said driven shaft ceases to rotate with said rotatable member, and a connection between said splined member and said clutch, comprising a lever, operating means 40 for said clutch comprising a shaft, a connection between said shaft and said clutch, an arm on said shaft adapted to be latched by said lever, a starting operating handle affixed to said shaft, and stop means for said machine comprising a 45 handle connected with said lever so as to move said lever to release said arm.

7. In a machine of the class described a drive shaft and a driven shaft, a clutch on said drive shaft and a connection between said drive shaft and said driven shaft including a member rotatable on said driven shaft, a member splined 50 on said driven shaft and having means for en-

gagement with said rotatable member, said engagement means being such as to produce axial displacement of said splined member if said driven shaft ceases to rotate with said rotatable member, a third shaft, an arm on said shaft for operating said clutch, a handle on said shaft and a latching arm on said shaft, a lever and means for pivoting said lever, one end of said lever engaging said splined member and the other end of said lever having means for interlocking with 10 said latching arm, spring means for urging the latching end of said lever downwardly, an operating handle, means for pivoting said operating handle and a connection between said handle and the latching end of said lever for urging said end 15 upwardly to release said latching engagement, said two operating handles being located in close proximity to each other.

8. In a machine of the class described having a frame, a horizontally disposed drive shaft and a 20 vertically disposed driven shaft, a clutch on said drive shaft, a power connection between said drive shaft and said driven shaft including a member rotatable on said driven shaft, a member 25 splined on said driven shaft having means for engagement with said rotatable member, said engagement means being such as to produce axial displacement of said splined member if said driven shaft ceases to rotate with said rotatable member, a pair of brackets mounted on said 30 frame, a shaft journaled in said bracket, and a pair of operating arms in close proximity, one of said arms fixed on said shaft for rocking movement in one direction, the other of said arms pivoted on one of said brackets for rocking movement in a transverse direction, an operative connection between said last mentioned shaft and said clutch, a lever also pivoted on said bracket and having an end engaging said splined member, a latching arm on said shaft and means for 35 effecting latching engagement between said lever and said latching arm, the functioning of said apparatus being such that a movement of one of said operating handles in one direction will engage said clutch and latch the latching arm 40 and lever, while the movement of said other operating handle in a transverse direction will release said latching engagement, said latching engagement being also releasable by movement of said lever upon displacement of said splined 45 member.

STANLEY R. ROSENDALE.
